UNITED STATES PATENT OFFICE.

CHARLES W. RASMUSSEN, OF CHICAGO, ILLINOIS.

CABLE-RAILWAY CAR.

SPECIFICATION forming part of Letters Patent No. 289,189, dated November 27, 1883.

Application filed February 13, 1883. (No model.)

To all whom it may concern:

Be it known that I, CHARLES W. RASMUSSEN, a citizen of the United States, residing at Chicago, in the county of Cook and State of Illinois, have invented certain new and useful Improvements in Cable-Railway Cars, of which the following is a full, clear, and exact description.

In a former patent, No. 266,198, granted to me on the 17th day of October, 1882, is illustrated a cable-railway car having a grip located centrally beneath the same, which is provided with mechanism whereby the grip may be operated from either platform of the car. In such patent the grip is shown as suspended from beams bolted to the bottom of the car, and necessarily, therefore, will partake of the movement of the car upon its springs. This vertical movement of the grip necessitates such an enlargement of the cable-tube as will permit it to play freely therein, and makes the cost of construction much greater than it would be were there no vertical movement of the grip.

The object of my present invention is to provide improved means whereby the grip may be sustained independent of the car-body, so that it will not be affected by the car-springs, and will therefore have little or no vertical movement. This object I have accomplished by the construction hereinafter described, illustrated in the accompanying drawings, and particularly defined in the claims at the end of this specification.

Figure 1 is a plan view of the under side of a cable-car having my improvements applied thereto. Fig. 2 is a view of the car in vertical longitudinal section. Fig. 3 is a detail view, in side elevation, of a portion of the car-bottom frame and subjacent parts.

A designates the bottom frame of the car-body, from which depend the hangers a, perforated at their bottom to receive the rods a', suitably connected to the car-frame. These rods a' pass through the flanges b on the outer side of the journal-box frame B, and carry the spiral springs a'', upon which the car-body is sustained. The front ends of these frames are curved, and to them are connected the end rods, B', and to the rear ends of the box-frames are bolted, as shown at b'', the side rods, B''.

These several parts B, B', and B'', connected thus together, form a rigid frame, which is sustained by the journal-boxes from the ends of the car-axles. Between the end rods, B', and connected thereto, are held the center rods, B³, braced by the tie-rods b³, and carrying the journal-blocks C, which support the journal C' of the grip C². The grip and its operating mechanism is of the construction set out in Patent No. 266,198, and need not be described in detail here.

From the foregoing construction it will be seen that the grip, being sustained by the supporting-frame connected to the journal-boxes, is not affected by the motion of the car upon its springs. A further advantage of this construction is that the weight of the grip is borne by the car-axles at the points best suited to sustain the weight. By my improved manner of sustaining the grip, it becomes possible to support the grip under the center of the car without cutting the car-body and without the necessity of a very large tube.

While I have illustrated, for convenience, in the accompanying drawings the form of grip and operating mechanism shown in my former patent, No. 266,198, it will be understood, of course, that the invention may be used in connection with other forms of mechanism by which a car is to be connected to a constantly-moving cable. It will also be understood that the details of construction of the supporting-frame may be varied within wide limits without departing from the spirit of the invention.

Having thus described my invention, what I claim as new, and desire to secure by Letters Patent, is—

1. In a cable-railway car, the combination, with the journal-boxes, the springs for supporting the body of the car, and mechanism for connecting the car with a moving cable, of a frame for sustaining said mechanism, supported upon the journal-boxes at the opposite ends of the car-axles, substantially as described.

2. In a cable-railway car, the combination, with the journal-box frames B, carrying springs for supporting the body of the car, of the end rods, B', the side rods, B'', and mechanism for connecting the car with a moving cable, substantially as described.

3. In a cable-railway car, the combination, with the cable-grip, of a frame for supporting said grip, connected to the journal-boxes of both ends of the car-axles, substantially as described.
4. In a cable-railway car, the combination, with the four wheels of the car, of a cable-grip located entirely beneath the bottom of said car, and a frame for supporting said grip, connected to the journal-boxes of said car-wheels on opposite sides of the car, substantially as described.
5. In a cable-railway car, the combination, with the car-axles and the grip, of the grip-supporting frame sustained upon the journals of said car-axles that sustain the car-body, and having the central rods extending from and to the end of said frame and adapted to carry the grip, substantially as described.

CHARLES W. RASMUSEN.
